UNITED STATES PATENT OFFICE.

ISAAC A. BAUM, OF CHICAGO, ILLINOIS.

PLASTER TERMINAL.

Application filed September 12, 1927. Serial No. 219,093.

My invention relates to plaster terminals and particularly to a novel one-piece sheet metal terminal.

It is well known that plaster terminals of all kinds and types have been presented to builders, with more or less success. One of the greatest difficulties in the past has been to produce a plaster terminal that will fit snugly over a rough buck, insure rigidity, and 10 accurate alignment.

The device of my invention is intended to overcome all the defects previously encountered in a device of this type. My invention consists of a single piece of sheet metal having a plurality of ears contacting one side of the rough buck, and the other angle contacting the other face of the rough buck. The metal is bent at right angles to the base member and terminates in a backwardly disposed 15 bead that functions not only as a plaster terminal, but also as an anchor for the adjacent plaster.

The device will be more readily understood by reference to the accompanying drawing, 20 in which;

Fig. 1 illustrates a perspective view of a device constructed in accordance with my invention.

Fig. 2 is a similar view of a modified construction showing the ears cut through the full width.

In the drawing, and referring particularly to Fig. 1, it will be seen that I have illustrated a rough buck, A, door jamb and stop, 35 B, and plaster C. The usual plaster support or lath is not shown. The device of my invention consists in a long, relatively narrow strip of metal having a base 10, plaster defining portion, 11 and plaster bead 12. Formed 40 out of the metal in said base, are the ears 13 which are bent at right angles to the plane of the base 10, on the line 14 at intervals along the length of the strip. The plaster defining portion 11 is formed at right angles to the base 10 on the line 14, and terminates in a longitudinal bead 12 which is bent back on itself to form less than a right angle with the plaster defining portion. This bead serves 45 to strengthen the edge against possible bending by being struck by objects during con-

struction, as well as to provide a secure anchor for the plaster which fills in behind it. The base 10 and the ears 13 are intended to contact the narrow and the wide faces respectively, of a rough buck and to insure a 55 firm and rigid contact for the plaster terminal. The ears and the base may be provided with apertures 15 to receive nails or other securing means.

In installation, the device is set up around 60 the corner of the rough buck and securely nailed in place. The finishing members, such as the door jamb and stop, may then be applied. Plaster C may then be applied over the lath or screen (not shown) the thickness of 65 the plaster being defined by the portion 11.

In Fig. 2 I have shown a slightly modified form of my invention, the only difference in the two being that the ears 16, 17 are longer and are cut through to the edge of the base. 70 By this modified device, a more certain and more rigid contact is had with the rough buck and the possibility of injury from a blow directly on the face of the portion 11 (Fig. 1) 75 is much reduced. Of the two forms here illustrated, the form indicated in Fig. 2 is considered the more preferable, being stronger and more easily handled, the ears 13 shown in Fig. 1 being of such small size as to be capable of easy destruction by contact in 80 shipping and handling.

The provision of the cut-away portions 16, 17, enables the insertion of wedges between the buck and the jamb without interference with the metal portion of the terminal. By placing the wedges at points between the portions 17, they may be positioned in the same manner as though the plaster terminal had no part projecting into that space. 85

Thus it will be seen that my invention provides a plaster terminal that is simply made, easily handled, easily installed by unskilled workmen, and highly efficient. The strips can be furnished in any desired length or cut 95 to any convenient size without destroying the efficiency thereof.

Obviously modifications and variations may be made in the design and construction here illustrated, and I do not wish to be lim- 100

ited except as indicated in the appended claim.

I claim:

A device of the class described consisting
5 of a strip of metal having a rebent outer
margin constituting a plaster anchor or bead,
the inner edge being slotted at intervals, alternate
10 sections of the slotted edge being bent
at right angles, the series of angularly dis-
posed sections being adapted to lie alongside
of and be secured to a wood frame member,
the portion of the strip between the bent sec-
tions and the bead constituting a plaster de-
fining terminal.

15 In testimony whereof I have affixed my signature.

ISAAC A. BAUM.
